UNITED STATES PATENT OFFICE.

JAMES O. CASADAY, OF SOUTH BEND, INDIANA.

INTERNAL-COMBUSTION ENGINE.

1,372,216.

Specification of Letters Patent.

Patented Mar. 22, 1921.

Application filed March 12, 1919. Serial No. 282,236.

To all whom it may concern:

Be it known that I, JAMES O. CASADAY, a citizen of the United States, residing at South Bend, in the county of St. Joseph and 5 State of Indiana, have invented certain new and useful Improvements in Internal-Combustion Engines, of which the following is a specification.

This invention relates to an improvement 10 in internal combustion engines of that type wherein the cylinders are arranged in coupled or associated pairs, with one cylinder of a pair utilized as a compression cylinder for the charge, and the other cylinder of the 15 pair serving as the firing or power cylinder.

In engines of this type, as heretofore generally proposed, it has been customary to transfer the charge from the compression cylinder to the firing cylinder before either 20 of such cylinders has reached the extreme limit of its stroke. This tends to prevent a complete scavenging of the firing cylinder, and compels the piston of such firing cylinder to aid in the compression of the charge.

25 The present invention arranges the cylinders and pistons of the respective pairs, so that the piston of the firing cylinder is in advance of the piston of the compression cylinder, so that the charge from the compression cylinder is delivered to the firing cylinder during the initial movement of the piston of the firing cylinder on the power stroke. This permits a full scavenging 30 stroke of the firing piston, delivers the charge under the full compression stroke of the compression piston, and fires the charge 35 when the crank of the firing piston is at the most effective point for leverage action.

The invention is shown in the preferred 40 form in the accompanying drawings, in which:—

Figure 1 is a vertical sectional view illustrating the invention.

Fig. 2 is a plan view of the same.

45 Fig. 3 is a diagrammatic view illustrating the relative positions of the pistons and cranks at firing point.

Fig. 4 is a similar view showing the position 50 of the crank of the firing piston at time of firing.

The improved construction is here shown as including the cylinders of one pair only, it being understood that any desired battery of cylinders may be used, when arranged in 55 associated pairs as described.

The firing cylinder 1 and associated com-

pression cylinder 2 are of any usual type or construction, and substantially of equal cubical area. A piston 3, hereinafter termed the power piston is arranged in the cylinder 1, while a similar piston 4, hereinafter termed the compression piston, is arranged in the compression cylinder. The power piston is given a lead over the compression piston, as will be clear from Figs. 3 and 4, in 60 that the crank 5 of the connecting rod 6 of the power piston is arranged in advance of the crank 7 of the connecting rod 8 of the compression piston. This degree of advance may vary in accordance with desired conditions, but the particular feature here involved is that the power piston will have reached the end of its stroke and reached a point approximately 45° over center before the firing occurs, at which time the compression piston will have completed its 65 stroke.

An inlet valve 9, involving any usual or preferred type of inlet valve structure, is arranged at the upper end and to one side of 80 the center of the compression cylinder, this valve being held closed by the usual spring, as 10, and being automatically opened by the suction of the compression piston in its down stroke. A similar exhaust valve 11 is 85 arranged at the top of the firing cylinder, this valve being also of any usual or preferred type, normally held closed by a spring 12. Any desired means (not shown) may be employed and properly timed to open 90 and hold open the exhaust valve to allow practically a full up stroke of the power piston, in order that a satisfactory scavenging action may be had.

A transfer valve is arranged on the engine 95 block between the inlet and exhaust valves, and this valve forms an important detail of the present invention. The valve involves a casing 13, integral with the block, and arranged at an angle to a line between the 100 inlet and exhaust valves with one end thereof integral with the exhaust valve, and the opposite end to one side of and spaced from the inlet valve. The end of the casing next the inlet valve is open and a valve bushing 14 is slidably fitted therein, a cap 15 removably closing and sealing the open end of the casing. The bushing 14 has an inward projection 16, formed to slidably receive a valve rod 17, terminally carrying a valve 18, 110 adapted to coöperate with a seat 19 formed at the end of the bushing. The valve opens

toward the firing cylinder, and the casing 13 is formed, together with the head of the engine block, with an opening 20, leading from the casing 13 to the firing cylinder said parts 5 being also formed with an opening 21, opening from the compression cylinder into the transfer valve casing. The valve is normally held closed by a spring 22, bearing between a removable fastening on the end of 10 the valve rod 17 and the projection 16.

In operation, as so far described, the compression piston, in its downward stroke draws in a charge through the inlet valve 9, the similar stroke of the power cylinder 15 being the firing stroke. On the up stroke, the pistons are of course moving in unison, with the power piston in advance. The power piston moves the full length of the up stroke to force out the spent gases, the exhaust valve being held open. During the 20 up stroke of the compression piston, the charge previously drawn in is compressed. During practically the full compression stroke, the transfer valve is held closed by 25 spring 22, until just before the up stroke of the compression piston is completed, the power piston, by starting the down stroke, overbalances the transfer valve, by the tendency to create a vacuum in the firing cylinder, the transfer valve is opened, and the 30 charge under full compression, and without the slightest diminution of the compression, as the compression piston is still moving upward, is forced into the firing cylinder. 35 Immediately the compression piston starts the downward stroke, the tendency toward a vacuum on this side with the pressure of the charge on the firing cylinder side of the valve, together with the power of the spring 40 22, instantly closes such valve. The engine is timed to fire at the particular moment following the closing of the transfer valve.

The power of the charge is thus directed 45 against the power piston when the crank operated thereby is at the point of most effective leverage, thus producing maximum power from the action.

The cylinders are of substantially the 50 same cubical area throughout their charging spaces, and this is important as a detail of manufacture. The transfer valve is arranged so that the free end of the casing thereof is readily accessible, in order that such valve may be removed for grinding or 55 other necessary repair or adjustment. The practically integral construction of the end of the transfer valve casing and that of the exhaust valve, permits the heat of the exhaust valve parts to be communicated to 60 the mixture passing through the transfer valve with well understood results. If desired, and as preferred, the interior of the transfer valve casing may be provided with small projections or points, as 23, to more 65 effectively radiate the conducted heat noted.

Having thus described the invention, what is claimed as new, is:—

1. An engine including an associated pair of cylinders of substantially equal cubical contents, pistons in said cylinders, means to 70 which the pistons are connected for power purposes, one of said pistons being connected to said means so as to travel in advance of the other, means for admitting a charge of gas to the cylinder having the 75 relatively retarded piston, an incased spring closed valve entirely incased within the engine, said spring closed valve being entirely controlled in its opening movement by the suction of the advanced piston for admitting 80 such charge following the compression by the retarded piston to the other cylinder as such advanced piston is started on its firing stroke, said valve being entirely controlled during its closing action by its spring. 85

2. An engine having a firing cylinder and a compression cylinder, a compression piston in the compression cylinder, a power piston in the firing cylinder, said power piston having a lead over the compression 90 piston, a substantially horizontally disposed spring closed transfer valve establishing communication between the cylinders, said transfer valve being entirely inclosed within the engine and controlled entirely in its 95 movement to open position against the action of its spring by the initial vacuum of the firing stroke of the power piston.

3. An engine having a compression cylinder with a compression piston therein, a 100 firing cylinder with a power piston therein, an inlet valve for the compression cylinder, an exhaust valve for the firing cylinder, a spring closed transfer valve substantially horizontally disposed and entirely incased 105 within the engine and establishing communication between the cylinders, said spring closed transfer valve being closed and held closed against the compression of the compression piston by its spring and 110 opened entirely by the suction of the firing piston as it starts its firing stroke.

4. An engine having a firing cylinder, a compression cylinder, a piston in each cylinder, an exhaust valve for the firing cylinder, 115 an inlet valve for the compression cylinder, and a spring closed transfer valve to establish communication between the cylinders, said transfer valve being entirely incased within the engine and entirely controlled in its movement to open position by the initial suction from the firing piston and in its movement to closed position by its spring, said valve having a casing in part substantially integral with the casing of the 120 exhaust valve to utilize heat of the latter for preheating the charge as it enters the firing cylinder. 125

5. An engine having a firing cylinder, a compression cylinder, a piston in each cylinder, 130

der, an exhaust valve for the firing cylinder, an inlet valve for the compression cylinder, and a spring closed transfer valve for establishing communication between the cylinders, said valve having a casing integral at one end with the casing of the exhaust valve and extended therefrom toward and at a distance from the inlet valve, whereby

the inlet end of said transfer valve casing is readily accessible, said spring closed transfer valve being entirely controlled during a transfer operation by the suction of the firing piston.

In testimony whereof I affix my signature.

JAMES O. CASADAY.
